UNITED STATES PATENT OFFICE

91,131

DESIGN FOR A DRESS

Mary Louise Caston, Chicago, Ill., assignor to
The Sterling Company, Chicago, Ill., a corporation of West Virginia

Application October 16, 1933. Serial No. 49,499

Term of patent 3½ years

To all whom it may concern:

Be it known that I, MARY LOUISE CASTON, a citizen of the United States, residing at Chicago, in the county of Cook and State of Illinois, have invented a new, original, and ornamental Design for a Dress, of which the following is a specification, reference being had to the accompanying drawing forming a part thereof.

Fig. 1 is a perspective front view of a dress embodying my design; and rear of the dress shown in Figure 1, the materials of the skirt portion, waist portion, and cuffs having the respective patterns illustrated in Figure 1.

I claim:

The ornamental design for the dress shown and described.

In witness whereof, I hereunto subscribe my name this 14th day of October, 1933, at Chicago, Illinois.

MARY LOUISE CASTON.
